Primary Examiner — George A Bugg*Assistant Examiner* — Tamara L Hahn(74) *Attorney, Agent, or Firm* — JCIP; Joseph G. Chu; Jeremy I. Maynard(57) **CLAIM**

The ornamental design for a pallet, as shown and described.

DESCRIPTION

FIG. 1 is a top perspective view of a pallet;

FIG. 2 is a bottom perspective view of the pallet;

FIG. 3 is a front view of the pallet;

FIG. 4 is a rear view of the pallet;

FIG. 5 is a left side view of the pallet;

FIG. 6 is a right side view of the pallet;

FIG. 7 is a top view of the pallet; and,

FIG. 8 is a bottom view of the pallet.

The broken lines in the drawings depict portions of the Pallet that form no part of the claimed design.

1 Claim, 8 Drawing Sheets
